[57] CLAIM

The ornamental design for a drum support, as shown and described.

DESCRIPTION

FIG. 1 is a top and right front isometric view of a first embodiment of a drum support showing my new design; FIG. 2 is an exploded top and right front isometric view of a drum support;

FIG. 3 is a front view thereof;

FIG. 4 is a left side view thereof;

FIG. 5 is a right side view thereof;

FIG. 6 is a top view thereof;

FIG. 7 is a bottom view thereof;

FIG. 8 is a rear view thereof;

FIG. 9 is a top and right front isometric view of a second embodiment of a drum support showing my new design;

FIG. 10 is an exploded top and right front isometric view of a drum support;

FIG. 11 is a front view thereof;

FIG. 12 is left side view thereof;

FIG. 13 is a right side view thereof;

FIG. 14 is a top view thereof;

FIG. 15 is a bottom view thereof; and,

FIG. 16 is a rear view thereof.
